(57) **CLAIM**

The ornamental design for an orthopedic plate for osteotomies, as shown and described.

DESCRIPTION

FIG. 1 is a front perspective view of an orthopedic plate for osteotomies showing my new design;

FIG. 2 is a right side perspective view thereof;

FIG. 3 is a rear side perspective view thereof;

FIG. 4 is a front side elevational view thereof;

FIG. 5 is a rear side elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The orthopedic plate for osteotomies is made of a metal (stainless steel, titanium) or nonferrous metal (aluminum). The orthopedic plate for osteotomies is used in orthopedic surgeries to assist in the correction of alignment and broken bones etc.
